[57] CLAIM

The ornamental design for a line marking gauge, as shown.

DESCRIPTION

FIG. 1 is a top, front, and right side perspective view of a line marking gauge showing my new design;

FIG. 2 is a bottom plan view;

FIG. 3 is a rear elevational view;

FIG. 4 is a left side elevational view; and

FIG. 5 is an enlarged fragmentary cross-sectional view thereof, taken along line 5—5 of FIG. 4.

FIG. 1

FIG. 2

FIG. 3

FIG. 4

FIG. 5
